INVENTOR.

August Roos.

United States Patent Office.

AUGUST ROOS, OF NEW YORK, N. Y.

Letters Patent No. 67,912, dated August 20, 1867.

IMPROVED APPARATUS FOR RECTIFYING SPIRITS.

The Schedule referred to in these Letters Patent and making part of the same.

TO ALL WHOM IT MAY CONCERN:

Be it known that I, AUGUST ROOS, of the city and State of New York, have invented, made, and applied to use a certain new and useful improvement in Rectifying Spirits; and I do hereby declare the following to be a full, clear, and exact description of the said invention, reference being had to the annexed drawing, making part of this specification, wherein—

Figure 1 is a section vertically of my improved rectifying apparatus, and

Figure 2 is a view of the rectifying tube broken open and in perspective.

Similar letters denote the same parts.

In the distillation and rectification of alcohol and spirits a still, *a*, has been used, heated by a steam pipe, *b*, the vapor rising through the rectifying column *c*, having caps *d* over the vapor-tubes to direct such vapor through the liquid upon the successive diaphragms, and the liquid has been returned by the overflow pipes *e* to the still, while the vapors have passed off either to a second rectifying column or to a condenser.

In almost all the condensers heretofore employed the vapors alternately ascend and descend, thereby coming into contact with the empyreumatic oils that condense before the spirit, and by that contact cause the spirit to receive or retain the taste and smell of such oils, or else they are condensed and pass away with the alcohol or high wines.

The object of my said invention is to more perfectly separate the empyreumatic oils and cause them to pass away in the opposite direction to the spirit, so that the objectionable smell and taste are removed as quickly as possible from the vapors, and do not come in contact with the alcohol as it is condensed.

In the drawing the vapors pass from the column *c*, through the pipe *g*, into a double case, the vapors being in the space between the cylinders *h* and *i*. This space is divided by segmental rings *k*, (see fig. 2,) placed alternately so that the vapors are checked and compelled to travel zigzag, and thereby the condensation is much more thorough of the impurities, the temperature being maintained by the water bath *l*, in which such column is placed, so that nothing but spirit-vapors will pass by the pipe *m* into the refrigerator *n*. The condensed vapors pass from the case *h* *i* back into the column *c*, by the pipe *o*, or, if desired, may be led back to the still through a pipe and cock, shown at *o'*, that connects with the pipe *p*. The refrigerator *n* is formed with a case that is double, with segmental rings *k*, the same as in the case *h* *i*, and the condensed spirit passes off by the tube *r*, into which a test-glass may be inserted.

This invention may be used for condensing the spirit in any part of the rectification or distillation of the same.

What I claim, and desire to secure by Letters Patent, is—

The rectifying condenser formed of the case *h* *i*, with the segmental rings placed alternately, to arrest the vapors as they pass up through said condenser; as and for the purposes set forth.

In witness whereof I have hereunto set my signature this 12th day of June, 1867.

AUGUST ROOS.
